R. ROEHM,
ADVERTISING SIGN,
APPLICATION FILED SEPT. 11, 1916.

1,227,074.

Patented May 22, 1917.

UNITED STATES PATENT OFFICE.

RICHARD ROEHM, OF NEWARK, NEW JERSEY, ASSIGNOR TO THE WHITEHEAD & HOAG COMPANY, A CORPORATION OF NEW JERSEY.

ADVERTISING-SIGN.

1,227,074.

Specification of Letters Patent.

Patented May 22, 1917.

Application filed September 11, 1916. Serial No. 119,476.

To all whom it may concern:

Be it known that I, RICHARD ROEHM, a citizen of the United States of America, and resident of Newark, in the county of Essex, 5 in the State of New Jersey, have invented new and useful Improvements in Advertising-Signs, of which the following, taken in connection with the accompanying drawings, is a full, clear, and exact description.

10 This invention relates to certain improvements in signs of a character particularly adapted for advertising purposes.

The primary object of the invention is to produce a sign of so striking and interesting appearance as to immediately concentrate the attention of even the casual observer and corollary thereto the production of a rigid, permanent structure in which the parts are assembled in a highly efficient 20 manner.

Other objects and advantages will appear from the following description taken in connection with the accompanying drawings:

Figure 1 is an elevation of a sign constructed in accordance with this invention.

Fig. 2 is a cross section on line 2—2, Fig. 1.

The sign comprises a plate, sheet or member —1— preferably formed of suitable metallic material, such as, tin, having letters, 30 designs, insignia, indicia or the like produced or formed in raised characters thereon. The top or maximum raised portion of the character is connected to the plate or the sheet by angularly disposed or slanting 35 walls.

In this specific illustration, a series of letters —2— constituting words are produced by pressing upwardly or raising portions of the sheet metal plate —1—, the angular or 40 slanting side walls —3— of the raised characters merging into the plate —1— and into the maximum raised portion of the letters.

The top of the plate about the letters is 45 preferably provided with rows of relatively small depressions —3'— preferably alined longitudinally, transversely and obliquely of the plate constituting reflecting surfaces about the letters or indicia.

The plate —1— is provided with a suitable 50 facing member —4— of transparent, flexible material as celluloid. The letters or indicia formed upon the plate —1— are reproduced upon the surface of the facing —4— by painting, lacquering or the like with an 55 opaque substance as indicated at 4'. The in-

dicia upon the facing should be of a size sufficient to cover and hide the top or upper surface of the indicia raised upon the plate but to disclose the slanting or angularly disposed side walls of the raised indicia leading 60 from the top of the indicia to the plate as clearly shown in —3—, Fig. 1.

The indicia may be produced upon the facing in solid colors or in several diverse colors, if desired, as indicated in connection 65 with the words "Radiant" and "Sign."

Preferably the surface of the facing or celluloid sheet surrounding the indicia is covered with a translucent lacquer or ink of suitable color, such as bronze, giving to the 70 underlying plate, with its depressions, a golden appearance.

A border —5— may be produced upon the facing —1— by means similar to those used in forming the indicia thereon and of the 75 same or different color as desired. The portion of the plate —1— underlying the border —5— is preferably bent backwardly somewhat at an angle to the top of the sheet to give a framing effect to the border. A 80

suitable backing sheet —6— is provided of suitable material, such as, cardboard and adapted to cover the rear surface of the plate —1— and prevent injury to the same. For the purpose of rigidly and permanently connecting all of the parts by substantially unitary means, the backing sheet —6— is 85 formed of a size substantially equal to that of the complete sign while the facing sheet is of somewhat greater extent and the intermediate plate —1— is of a size somewhat 90 larger than the facing sheet. The flange —7— is then formed upon the plate —1— and bent into contact with the adjacent edge portion of the facing sheet to confine such 95 edge. The backing —6— is then placed in position and the edge —8— of the plate —1— with the edge portion of the facing sheet having a part confined by the flange —7— is bent backwardly until in contact 100 with the backing —6— to confine the same. The bending backwardly of the flange —8— also tensions the facing to the desired extent.

By this construction the flanges formed 105 upon the intermediate plate —1— are utilized for permanently and rigidly connecting all the parts of the sign and by reason of their integral nature and immobility with respect to the plate —1— upon which 110

the raised characters are formed, efficiently hold the indicia or letters upon the facing sheet in exact registration with the top portion of such raised characters leaving the 5 angularly disposed side portion of the letters uncovered and disclosed.

Although I have shown and described one particular construction and one particular method of producing a sign of this invention 10 in its preferred embodiment, I do not desire to limit myself to any specific construction, method of production or arrangement of the parts as various changes may be made in the details of each without departing from the 15 spirit of this invention as set forth in the appended claims.

What I claim is:

1. A sign comprising a metallic member 20 having raised portions in the form of a character or design, a facing member having opaque portions registering with said raised portions and translucent portions surrounding the opaque portions, and means for rigidly connecting the metallic member and the 25 facing member.

2. A sign comprising a metallic member having raised portions in the form of a character or design, a facing member having opaque portions registering with said raised 30 portions, and portions about the opaque portions having a coating of translucent colored lacquer, and means for rigidly connecting the metallic member and the facing member.

3. A sign comprising a metallic member 35 having raised portions in the form of a character or design, a facing member having opaque portions only partially covering said raised portions and translucent portions surrounding the opaque portions, and means for rigidly connecting the metallic member and the 40 facing member.

4. A sign comprising a metallic member having raised portions in the form of a character or design, a facing member having 45 opaque portions only partially covering said raised portions, and portions about the opaque portions having a coating of translucent colored lacquer, and means for rigidly connecting the metallic member and the 50 facing member.

5. A sign comprising a metallic member having indicia raised thereon, said raised indicia formed with top portions and inclined side walls, a translucent facing member having opaque portions registering with the top 55 portions of the raised indicia.

6. A sign comprising a metallic member having raised portions in the form of a character or design surrounded by a multiplicity of relatively small depressions, and a translucent facing member having opaque portions 60 partially covering the raised portions on the metallic member.

7. A sign comprising a metallic member having raised portions in the form of a character or design surrounded by a multiplicity of relatively small depressions, a translucent facing member having opaque portions covering the central parts only of the raised portions on the metallic member, a backing 70 member, means for preventing relative movement of the metallic member and the facing member.

8. A sign comprising a metallic member having indicia raised thereon, said raised 75 indicia formed with top portions and side walls, a facing member having opaque portions registering with the top portions only of the raised indicia, and portions about the opaque portions having a coating of translucent colored lacquer, and means for rigidly 80 connecting the metallic member and the facing member.

9. A sign comprising a metallic member having raised portions in the form of a character or design surrounded by a multiplicity of relatively small depressions, a facing member having opaque portions registering with the raised portions, and portions about the opaque portions having a coating of 90 translucent colored lacquer, and means for rigidly connecting the metallic member and the facing member.

In witness whereof I have hereunto set my hand this 7th day of September, 1916.

RICHARD ROEHM.
